DEAD LATCHING MECHANISM

Gotthard Hagstrom, Greenwich, Conn., assignor
to The Safe Padlock and Hardware Company,
Lancaster, Pa., a corporation of Pennsylvania

Application November 15, 1950, Serial No. 195,824

12 Claims. (Cl. 292—169)

1

My invention relates to certain improvements in dead latching mechanisms; and the nature and objects of the invention will be readily recognized by those skilled in the arts to which it relates in the light of the following explanation and detailed description of the accompanying drawings illustrating what I now believe to be the preferred embodiment or mechanical expression of the invention from among various other forms, arrangements, designs, embodiments, modifications, variations, combinations and constructions, of which the invention is capable within the broad spirit and scope thereof as defined by the appended claims.

The invention is directed more specifically to those types of dead latching mechanisms which utilize a so-called dead latch or auxiliary bolt member in cooperation with the main latch bolt of a door latching mechanism. In such types of dead latching mechanisms, the auxiliary or dead latch bolt member is so mounted and arranged that upon closing of a door with the main latch bolt projected into its keeper, the dead latch bolt is depressed by engagement with the strike plate and thereby actuates a dogging member into position dogging and locking the main latch bolt against forceful depression to a position cleared from the keeper and unlatching the door. Such dead latching mechanisms as now generally available are usually characterized by the fact that whenever the door which mounts such mechanism is in closed position with the dead latch bolt depressed by engagement with the strike plate, the dead latching dog member is also actuated to dogging position. When it is realized that a door latch mechanism after installation on a door may never be subjected throughout its installed life to any attempts to forcefully retract the latch bolt, it follows that the continual actuation of the dead latching dog to dogging position each time that the door is closed is a totally unnecessary and completely inefficient operation. Such continual dead latching dog actuation tends to wear out the mechanism and reduce the effective life thereof, as well as calling for complication of mechanism for effecting such continual dogging.

It is, therefore, a primary object of my invention to provide a dead latching mechanism in which the dead latching dog member thereof is never actuated to dogging position unless and until an attempt is made to force the main latch bolt of the door latch mechanism from latching position in its keeper with the door closed.

Another object is to provide a dead latching mechanism in which the mechanism is conditioned and set up for operation of the dead latch-

ing dog member to dogging position whenever a door is in closed position but in which the dog is never actuated to dogging position from its normal, undogged position unless an attempt is made to force the latch bolt from door latching position in its keeper.

Another object is to provide a dead latching mechanism of a type utilizing a strike engaged and actuated dead latch or auxiliary bolt, in which mechanism such auxiliary bolt performs no function in the actual operation of the dead latching dog between dogging and non-dogging positions, but merely serves to condition dog engageable structure for engagement by the dog when the latter is actuated to dogging position.

A further object is to utilize the main latch bolt retracting member of the latch mechanism to actuate the dead latching dog from dogging position to its normal, non-dogging position upon release from the main latch bolt of depressive forces that may be applied to the tip thereof when the door is in closed position with the latch bolt in its keeper.

A further object is to provide such a mechanism in which the biasing spring of the latch bolt mechanism for projecting the latch bolt, is utilized to bias the dead latching dog to dogging position.

A further object is to provide a design of such a mechanism in which the dead latching dog is mounted on the tail-piece of the main latch bolt of the latching mechanism.

A further object is to provide a dead latching mechanism of the dead latch bolt type which is of extreme mechanical simplicity with a minimum of parts capable of low cost manufacture and which can be readily assembled with the latch bolt mechanism.

With the foregoing and various other objects, features and results in view which will be readily recognized from the following detailed description and explanation, my invention consists in certain novel features in design and construction of parts and elements, and in combinations and sub-combinations thereof, all as will be more fully referred to and specified hereinafter.

Referring to the accompanying drawings, in which similar reference characters refer to corresponding parts throughout the several figures thereof:

Fig. 1 is a view in horizontal section through the free edge portion of a door and showing in top plan a knob operated latch bolt unit incorporating a dead latching mechanism of my present invention.

Fig. 2 is a view in vertical longitudinal section through the latch bolt unit of Fig. 1, taken as on

the line 2—2 of Fig. 1, and showing the dead latching dog in the non-dogging position thereof assumed with the door open and both the latch bolt and dead latch bolt in projected positions.

Fig. 3 is a view in transverse, vertical section through the latch bolt unit of Fig. 1, taken as on the line 3—3 of Fig. 2.

Fig. 4 is a view in transverse, vertical section, taken as on the line 4—4 of Fig. 2.

Fig. 5 is a view in horizontal, longitudinal section through the latch bolt unit, taken as on the line 5—5 of Fig. 2, a portion of the latch unit case wall, together with a portion of the bolt actuating yoke, the roll back and the knob spindle, having been broken away and removed.

Fig. 6 is an exploded view showing in perspective and in separated relation, the several parts and components making up the latch bolt unit and dead latching mechanism of Figs. 1 to 5.

Fig. 7 is a view similar to Fig. 2, but showing the dead latch bolt in retracted position with the dead latching dog conditioned for dogging operation upon depression of the latch bolt.

Fig. 8 is a view similar to Figs. 2 and 7, but showing the dead latching dog in latched or locked position as a result of depression of the latch bolt when the dead or auxiliary bolt is in depressed position.

Fig. 9 is a view in horizontal, longitudinal section through the latch bolt unit of Fig. 1, showing the latch bolt in door latching position in the keeper and the auxiliary bolt depressed by engagement with the strike plate when the door is closed.

A latch bolt unit of the door knob operated type, and embodying one possible exemplification of dead latching mechanism of my invention, is disclosed herein by way of example, in a form primarily designed and intended for use with a so-called outside door in which the latch bolt is adapted to be locked against retraction by suitable key controlled locking means when the door on which the unit is mounted is closed. The dead latching mechanism is not, however, in any sense restricted or limited to embodiment in or adaptation to either door knob actuated latch bolt mechanisms or to use with latch bolt units on outside doors. Latch bolt units of the illustrated example may be used on inside doors or for any desired type of closure, and in addition, the principles and features presented to the art by the invention may be expressed mechanically and structurally in various other forms and adaptations than that of the specific embodiment thereof of this example.

In the example embodiment, a tubular latch bolt unit L is utilized of a type embodying the inventions as disclosed and claimed in my co-pending U. S. patent application Serial No. 178,897, entitled Door Latch Mechanism. This unit L basically embodies an elongated, rectangular case C comprised of a body 10 stamped or formed in any suitable manner from sheet material to provide a vertical side wall 10a, top wall 10b, bottom wall 10c and an open side closed by a suitable cap or cover plate 11. The case C is closed at its inner end by an end wall 10d formed on body 10, and is open at its forward end at which there is secured a vertically disposed, rectangular, composite face plate structure 14. The case C mounts therein a roll-back 15 for rotation about a horizontal axis disposed transversely of the case, the roll-back 15 being rotatably mounted on a suitable bearing forming hub member 15a secured in vertically disposed position in the case.

Roll-back 15 is provided with a rectangular opening 16 formed axially therethrough in axial alignment with an opening 15b formed through the hub. At its upper and lower sides roll-back 15 is provided with vertically disposed lugs or cam members 17, respectively, which project into and through suitable openings formed in the top and bottom walls, 10b and 10c of the case body 10. The vertical side wall 10a of body 10 and the cover plate 11 are formed with openings 16a therethrough in axial alignment with roll back opening 16 and hub opening 15b, for receiving therethrough the rotatable latch bolt actuating spindle S (see Figs. 1 and 2), in the general manner familiar in this art.

The vertically disposed side wall 10a of case body 10 is formed with a laterally, outwardly projected or offset side wall portion 18 which is disposed longitudinally thereof and which extends from, and opens through the forward open end of the case C, to a location adjacent but spaced forwardly from opening 16a in case body wall 10. At its inner end the auxiliary bolt housing 18 is closed by an end wall 18a which joins and merges with wall 10a and the housing side wall 18. The wall portion is transversely curved to form a concave channel at its inner side with the contour at its outer side being convex. This outwardly offset wall portion 18 forms both a housing and a slide and guideway of U-shape cross section, for slidably receiving therein an auxiliary or dead latch bolt D, as will be referred to and described hereinafter.

A roll-back actuated, latch bolt retracting yoke member 20 of generally elongated, rectangular form is slidably mounted and confined within case C. This yoke member 20 includes a vertically disposed body wall 21 having an elongated opening 21a therethrough disposed longitudinally thereof. Wall 21 in assembled position of the yoke member in the case C is disposed and slidably between the adjacent inner side of roll-back 15 and the cap or cover plate 11 of the case, as will be clear by reference to Figs. 3 and 4.

At its rear end between hub bearing member 15a and the inner end wall 10d of case C, the yoke member 20 is bent inwardly for its full width to form the vertically disposed flange 22 thereacross which has at its free edge, slidable bearing engagement with the inner surface of case side wall 10a. Yoke member 20 at the forward upper side of wall 21, has an inwardly bent, horizontally disposed finger or lug 23, which lug has slidable bearing engagement at its free end with the inner side of case wall 10a. At its forward, lower side yoke member 20 is formed with an inturned flange portion 24 which is vertically disposed and located in a vertical plane passing through the rear edge of the horizontally disposed lug 23 thereabove. The inner free end of flange 24 has slidable bearing engagement with the inner side of case wall 10a, and the flange is formed with a rectangular opening 25 therethrough at the outer side portion thereof, with such opening being extended a slight distance rearwardly into the yoke body wall 21. Yoke member 20 thus bridges roll-back 15 and hub member 15a, with the rear flange 22 and forward flange 24 providing the positioning and bearing supports for reciprocation of the yoke member within the case C. Yoke member 20 has lateral guiding support in the direction outwardly toward cover plate 11 by slidable engagement with the inner side, flat surfaces provided by such cover plate.

The yoke member 20 has bent upwardly therefrom at the upper and lower side edges of body wall 21, the upwardly and downwardly projected ears 20a, respectively. Ears 20a are located on wall 21 intermediate the elongated opening 21a and in positions at the rear of end engaged by the upper and lower lugs or cams 17, respectively, of the roll back 15 (see Fig. 2). Hence, in assembled position, rotation of the roll-back 15 in either direction will cause the rearwardly moving lug 17 to engage its yoke mounted ear 20a to thereby force or slide the yoke rearwardly in case C for latch bolt retraction.

The latch bolt B of the latch unit L, may be considered to be of generally conventional design to provide the usual inclined face or surface for slidably engaging against the strike plate 2 of a door frame. In this instance, latch bolt B is slidably positioned in and guided by a rectangular opening 14a formed through face plate 14 in alignment with the forward, open end of case C. The latch bolt B has suitably connected to the rear end thereof, a tail-piece 30 which extends inwardly a distance and through the case C, and which is provided at its inner end with an upwardly projected nose forming a yoke engaging hook 31. In this example, the tail-piece 30 is of rectangular cross section (see Fig. 4). The hooked inner end 31 of tail-piece 30 extends in assembled position into the rectangular opening 25 of the forward flange 24 of yoke member 20, in a position with the upwardly extended nose member of the hook 31 engagable against the inner side edge portion 24a at the upper side of opening 25. Thus, upon rearward movement of yoke 20 the hooked inner end 31 of the tail-piece 30 being engaged with yoke member 20 at 24a, will draw the tail-piece rearwardly to retract the latch bolt B. But, latch bolt B with tail-piece 30 is movable rearwardly relative to and independently of yoke member 20 by rearwardly acting forces applied to the latch bolt at the forward, outer end thereof. Under such conditions tail-piece 30 slides freely rearwardly through yoke member opening 25 completely independently of the yoke member.

A coil expansion spring 32 is mounted on and over tail-piece 31 under compression between the rear side of the latch bolt B and flange 24 of yoke member 20. Hence, the latch bolt B when depressed or moved inwardly relative to yoke member 20 places spring 32 under an increased degree of compression, so that, upon release of the inwardly acting forces on the latch bolt the latter is instantly projected outwardly to normal, strike engaging, door-latching position (see Fig. 2).

Yoke member 20 is spring loaded and normally continuously biased to its forwardly projected position, as shown in Fig. 2. The spring loading is effected, in the example embodiment, by a coil expansion spring 33 which is inserted under compression within case C between the inner end wall 10d of the case and the inner end flange 22 of yoke member 20. When the roll-back 15 is rotated in either direction, yoke member 20 is forced rearwardly against and compresses spring 33 and the latch bolt B is retracted. Upon release of the turning forces on roll-back 15, spring 33 acts to instantly move the yoke member 20 forwardly to normal, latch bolt projected position. It is important to note that when latch bolt B is retracted by rearward movement of yoke member 20 against spring 33, the spring 32

is not further compressed as under these conditions latch bolt B and tail-piece 30 do not have movement relative to yoke member 20, so that, the spacing between yoke member flange 24 and the rear or inner side of latch bolt B does not change but remains constant. However, when latch bolt B is depressed and retracted independently of yoke member 20, the spring 32 is further compressed. In order to permit of such compression, spring 33 must not yield to the forces applied to yoke member 20 by spring 32, hence, spring 33 is formed heavier so as to exert a force greater than the maximum force exerted on the yoke by the spring 32. The foregoing conditions are utilized by my present invention is effecting the dogging or locking of the latch bolt B, in a manner to be referred to hereinafter.

By my invention I provide for dead latching, that is, locking the latch bolt B against depression to a sufficient degree when in door latched position in the keeper of the strike plate 2, to permit of the bolt being disengaged from the keeper in order to open the door. I effect this dead latching of the latch bolt unit L of the example embodiment, by the addition to the latch mechanism of unit L, of only two major elements or components, namely, a dead latching dog 50 and the dead latch or auxiliary bolt D. I utilize elements of the latch bolt mechanism of unit L for mounting and for the operative functioning of the dead latching dog 50 without requiring the addition of other elements or mechanism. I utilize the case C of the unit L for dogging engagement by the dog 50, thus eliminating the necessity for additional structure for this purpose. And I utilize the dead latch or auxiliary bolt D for the purpose solely of conditioning or making accessible to the dog 50, the dog engaged portion of case C, so that, bolt D performs no dog actuating functions and thus becomes an unloaded member, except for its depression by engagement with the strike plate 2 and its projection by a light biasing spring associated therewith.

The dead latching dog 50, referring to Fig. 6 in particular, comprises a generally L-shaped member having the vertically disposed mounting leg 51 and the generally horizontally disposed dogging arm 52. The outer end length of arm 52 is formed of a cam portion 53 which extends upwardly from arm 52 at an angle of approximately 45° thereto. At the outer end of cam portion 53, the arm terminates in a vertically upwardly extended dogging lug 54 which is of reduced width relative to the width of the arm to provide at one side of the lug a horizontally and transversely disposed shoulder 54a.

The dead latching dog member 50, referring now to Figs. 2, 4, 7 and 8 in particular, is in accordance with my invention, mounted on the tail-piece 30 of the latch bolt B by extending tail-piece 30 through the rectangular opening 51a in the mounting leg 51 of the dog, with such mounting leg being positioned at the forward end of the tail-piece between the forward end of spring 32 and the rear side of bolt B. The dog 50 is thus positioned and mounted on tail-piece 30 with the mounting leg 51 extended vertically upwardly therefrom and the dogging arm 52 extending generally horizontally and rearwardly through the case over and above spring 32, and between that spring and the top wall 10b of case C. The rear end of arm 52 extends under the horizontally disposed forward finger or lug 23 of

yoke 20, between that leg and the upper edge surface of the forward flange 24 of the yoke. In such position the dogging lug 54 of dog 50 extends upwardly into a non-dogging position, as shown in Fig. 2, with its upper edge lying immediately adjacent but slightly below the under surface of the top wall 10b of case C and with its rear vertical surface engaged against the rear edge surface 23a of lug 23 of yoke 20.

Thus mounted, due to the vertically elongated opening 51a in mounting leg 51, the dogging member 50 has limited rocking movement on tail-piece 30 to swing arm 52 upwardly and downwardly and thus raise and lower lug 54 toward and from case top wall 10b. As the mounting leg 51 is spring loaded and continually biased forwardly toward latch bolt B by spring 32, it follows that if the free end of arm 52 is unconstrained then the spring 32 will maintain arm 51 in forwardly rocked position against the rear side of latch bolt B with the arm 52 and dogging lug 54 being in their maximum upwardly swung position. Such position, which is the dogging position of dog 50, is shown in Fig. 8.

With the latch bolt mechanism of unit L in its normal position with the latch bolt B fully projected, the dog member 50 is rocked downwardly and rearwardly on tail-piece 30 against the force of spring 32 by the camming engagement of leg 23 of yoke 20 with the upper camming surface 53a of the cam portion 53 of dog arm 52. This position is shown in Fig. 2, with the dogging lug 54 in its non-dogging, lowered position at the under side of top wall 10b and engaged at its forward side with the rear edge portion 23a of the finger or lug 23.

The upper wall 10b of case C is utilized to provide structure engaged by the dogging lug 54 of dog 50, when the dog is actuated to move dogging lug 54 upwardly to its dogging position. In this example, a hole or opening 55, preferably rectangular as shown, is provided in and through top wall 10b of case C in position above and for receiving therein the dogging lug 54 of dog 50. The top wall 10b forms across the rear side of this opening 55, a contact or abutment edge 55a for dogging engagement by lug 54 of dog 50 when the dog is actuated to dogging position. Thus, when the latch bolt B is depressed by inwardly acting forces applied to the outer end thereof, tail-piece 30 of the latch bolt is displaced rearwardly relative to and independently of yoke member 20, and the dead latching dog 50 is also moved rearwardly with the tail-piece and bolt B. This rearward movement displaces the camming portion 53a and dogging lug 54 of arm 52 rearwardly, so that, under the action of the forces of spring 32, the dog 50 is rocked forwardly and the dogging lug 54 is projected upwardly into the opening 55. Continued depression of latch bolt B and rearward movement of tail-piece 30 and dog 50 is stopped by engagement of the rear side of lug 54 with the abutment edge 55a across the rear side of opening 55. Thus, the latch bolt B is dogged and locked against further depression. The design and relative positioning of the several elements and components effected by and participating in this dogging action, is such that from its normal projected position, latch bolt B is permitted but relatively slight inward depression before dogging is effected by engagement of the dogging lug 54 with the abutment edge 55a provided by case wall 10b. Upon release of the depressive forces acting on latch bolt B, spring 32

acts to return bolt B to its normal projected position, and by so doing dogging member 50 is thereby moved forwardly, so that, the camming surface 53a of camming portion 53 of dog arm 52 engages with the rear edge portion of arm 23 of yoke 20, and is thereby cammed downwardly to displace lug 54 from opening 55, to the non-dogging position as shown in Fig. 2.

In this instance, the width of the hole or opening 55 in the case side-wall 10b is but slightly greater than the dogging lug 54 of dog 50 which is to be received therein. Thus, when the dog 50 is rocked upwardly to position with the dogging lug 54 received in opening 55, the shoulder 54a of the dog may serve as a limiting stop by slidably engagement with the under surface of wall 10b.

The dead latch or auxiliary bolt D, referring now to Figs. 3, 4 and 6 in particular, may be formed or pressed-up from relatively thin gauge sheet material, such as sheet brass. The bolt D is comprised of a main body 60 of U or channel shape in cross section, having a transversely curved or convex outer side surface complementary to the concave inner side surface of the channel or slideway formed by the housing 18 of case C. The bolt D has a length less than the slideway formed by housing 18 and is freely slidably mounted and received in such housing for reciprocation longitudinally therein. The face plate 14 of the latch unit L is formed with an opening 14b therethrough as a lateral extension of the latch bolt receiving opening 14a, with the opening 14b aligned with the open forward end of the slideway formed by housing 18. The auxiliary bolt D in mounted position may thus reciprocally extend forwardly through opening 14b to a position projected outwardly beyond face plate 14.

The main U-section body member 60 of auxiliary bolt D has for a distance along its upper side wall, an upwardly projected guide flange 61 located along the inner edge of the upper side wall and being adapted to slidably engage over the adjacent inner side surface of case side wall 10a along the upper side of the channel formed by housing 18. Intermediate its ends, bolt body 60 is provided at the inner side thereof with a laterally offset side wall 62 which extends across the channel formed therein. At its forward end 50 the wall 62 has an inturned flange portion 63 extended into the channel of body 60, to form with wall 62a a forwardly closed housing for a light biasing spring 64. The outer side wall of body 60 is formed with an opening 60a therethrough (see Figs. 3 and 5). A lug 64a is bent up from side-wall 18a of housing 18 and projects inwardly therefrom.

When dead-latch bolt D is in mounted, assembled position in the guideway of case C formed by housing 18, the lug 64a extends inwardly through side opening 60a of body 60 of the bolt and the biasing spring 64 is confined within the housing provided by wall 62 under compression between lug 64a engaged by the rear end of the spring and end wall 63 engaged by the forward end of the spring. In such assembled position the forward length of bolt D projects outwardly through opening 14b of face plate 14 for a distance substantially equal to the distance of normal projection of the main latch bolt B, as will be clear by reference to Figs. 1 and 5. The outer end of the bolt D may be closed by a suitable end wall 65 which provides an abutting surface for engagement with the strike plate 2. The inner side of the latch bolt D is formed with a shoulder

66 thereacross which, with the bolts B and D in assembled position, is engaged by the forward outer side of end wall 63 of the spring receiving housing 62 or bolt D. In normal position as shown in Fig. 5, bolts B and D are projected forwardly from face plate 14 by their respective biasing springs 32 and 64. However, when latch bolt B is retracted by yoke member 20 the dead-latch or auxiliary bolt D, due to the engagement of shoulder 66 against wall 63, will be retracted as a unit with bolt B.

The sole purpose of the auxiliary bolt D is to condition, that is to open or to block-off, the opening 55 of case wall 10b which is adapted to receive therein the dogging lug 54 of dog 50. To this end, I provide bolt D at its inner rear end portion and on the upper side thereof, with a horizontally disposed plate or cover member 70 which is positioned on bolt D, so that when the bolt is in forwardly projected position, the plate 70 is located below and closes or blocks off opening 55 against the entry thereinto of the dogging lug 54. When, however, auxiliary bolt D is depressed and forced inwardly a sufficient distance, the plate 70 is moved rearwardly to a position removed from position blocking opening 55 and thus conditioning that opening for upward movement thereinto of the dogging lug 54 of dog 50. Such position is shown in Fig. 7.

A latch bolt unit L incorporating the dead latching mechanism of my invention, is shown in Fig. 1, in mounted and installed position in a door A. The latch bolt unit L is mounted in the usual manner in the door A with the face plate 14 thereof attached at the outer free edge of the door and with the main latch bolt B and auxiliary bolt D reciprocal to and from normal, projected positions through the face plate. A usual squared spindle S extends through the door and the square opening 16 in the roll-back 15, so that rotation of the spindle in either direction will effect retraction of latch bolt B and the auxiliary bolt D as a unit. The ends of spindle S at opposite sides of the door A mount the usual inner knob I and outer knob O. Any suitable key controlled locking means not shown may be provided for locking the spindle S against rotation by outer knob O, in a manner familiar in the art.

The unit L is shown in Figs. 1, 2 and 5, in the normal projected positions assumed by bolts B and D when the door A is in an open position. When the door is in closed position, either locked or unlocked, the latch bolt B, referring now to Figs. 7, 8, and 9, is projected into the keeper formed in the strike plate 2 in the usual manner to latch the door against opening. The dead-latch or auxiliary bolt D, however, is engaged at its outer end with the strike plate 2 as the door is closed and is depressed thereby to the position shown when the door reaches its closed position. Depression and rearward displacement of auxiliary bolt D moves plate 70 thereof to a position to the rear and clearing dogging opening 55 in the top wall 10b of case C, as shown clearly by Fig. 7. In this manner, the opening 55 is conditioned for dogging action of the dog 50. In the position of Fig. 7, with latch bolt B projected the lug 23 of the yoke member 20 constrains dog 50 to its rearwardly and downwardly rocked position against the force of spring 32, so that, the dogging lug 54 is located below and clear of top wall 10b and the opening 55 therein. In such position it will be obvious that normal latch bolt retraction by rotation of spindle S

may be effected without releasing dog 50 for upward swinging to dogging position. This is so because rearward movement of yoke member 20 by the action of spindle S will retract latch bolt B without changing the relative positions of the yoke member and the latch bolt.

With the mechanism in the door closed and latched position of Fig. 7, if an attempt is made to forcefully depress latch bolt B from its position in its keeper in strike 2, as by inserting a knife or thin blade between the strike and face plate 14, the bolt B with tail-piece 30 will be moved inwardly relative to and independently of yoke member 20 which will thus move dead-latching dog 50 rearwardly to a position unconstrained by the yoke lug 23, so that, spring 32 acts instantly to rock dog 50 forwardly and upwardly and thereby project dogging lug 54 into opening 55. Further depression of latch bolt B will then be prevented by engagement of lug 54 with surface 55a of wall 10b, and the bolt will be effectively locked against further depression and displacement from its keeper. In such operation with the door closed, plate 70 has been moved by the depressed, auxiliary bolt D to a position clearing opening 55 for entry thereinto of the dogging lug 54.

Thus, the dead-latching mechanism of my invention under all normal conditions is never actuated to dogging position until an attempt is made to depress latch bolt B from its door latching position in its keeper in the strike 2.

Attention is directed to the fact that if end pressure is applied to the latch bolt B when the door is shut, or the friction against the latch by the strike 2 is so great as to prevent the latch bolt from extending fully into the strike, or sufficient clearance in the material of the door behind the strike plate 2 has not been provided, it may be possible that the dead-latching dog 50 will be actuated to swing the dogging lug 54 into the opening 55 of case side wall 10b. Under these conditions the dogging lug 54 might remain in dogging position in the opening 55. However, rotation of the spindle S by one of the knobs mounted thereon will cause the yoke member 20 to move and the lug 23 carried by the yoke member will then slide onto the camming surface 53a and cause dog 50 to be rocked downwardly out of dogging position, thus permitting the latch bolt B to be withdrawn. The movement of the yoke member 20 caused by rotation of spindle S will always result in retraction of latch bolt B regardless of the position of the dead-latching dog 50.

With the door A in open position, both the latch bolt B and the auxiliary bolt D are in their fully projected positions, as shown in Fig. 1. When the door A is swung to closed, latched position, the latch bolt B is in the usual manner by engagement with the strike 2, depressed as it moves across the strike to closed position until it is aligned with and projects into the keeper provided by the strike. As latch bolt B is depressed it also depresses auxiliary bolt D. The depression of latch bolt B is independent of yoke member 20, and may effect dogging operation of dog 50 in a manner hereinbefore explained. However, as will be noted from Fig. 2, when both bolts B and D are projected the dog blocking plate 70 of auxiliary bolt D is over dogging lug 54, that is, between that lug and case wall 10b. As bolts B and D are simultaneously depressed, it follows that the blocking relationship of plate 70 to dogging lug 54 remains as shown in Fig. 2 so that

any dogging action of dead latching dog 50 is rendered ineffective. As soon as the latch bolt B in the door closing operation is aligned with the keeper in the strike 2, it projects into that keeper so that dog 50 assumes non-dogging position under the action of lug 23, while the auxiliary bolt D remains depressed by engagement with the strike plate 2. The blocking plate 70 of bolt D thus remains positioned removed from opening 55, so that dogging action may thereafter take place if an attempt is made to depress latch bolt B from the keeper.

It will also be evident to those skilled in the art, that various changes, modifications, substitutions, eliminations and additions may be resorted to without departing from the broad spirit and scope of my invention, and, hence, it is not my intention to limit the invention in all respects to the exact and specific disclosures of the example embodiment herein illustrated and described, except as may be required by clearly intended specific limitations thereto included in any of the appended claims.

What I claim is:

1. In a latch bolt mechanism, in combination, a case; a latch bolt including, a tail-piece mounted in said case for reciprocation to and from a projected, latching position; means for retracting said latch bolt including, a yoke member reciprocally mounted in said case and being engageable with said latch bolt tail-piece to retract said latch bolt from said projected position; said latch bolt and tail-piece being depressible from said projected position independently of said yoke member; a coil expansion spring mounted on said tail-piece under compression between said latch bolt and the adjacent end of said yoke member and being adapted to continuously bias said latch bolt to its projected position; a dogging member comprising a leg mounted on said tail-piece between said latch bolt and said spring in position extended radially from and being rockable on said tail-piece in directions axially thereof, a dogging arm extended laterally from said leg inwardly and axially of said tail-piece, and a dogging lug at the free end of said arm extended laterally outwardly therefrom toward said case; said dogging member being rockable on said tail-piece to move said dogging lug outwardly to a dogging position and inwardly to a non-dogging position; said spring acting to continuously bias said dogging member to dogging position; said case being formed to provide a fixed abutment to be engaged by said dogging lug in dogging position thereof; and means on said yoke member adapted to be engaged by said dogging member to constrain said member to non-dogging positions when said latch bolt is in projected position.

2. In a latch bolt mechanism, in combination; a case; a latch bolt mounted in said case for reciprocation to and from a latching position projected from the case; a spring unit adapted to continuously bias said latch bolt to said projected position; mechanism for retracting said latch bolt from its said projected position; said latch bolt being depressible from projected position independently of said retracting mechanism; a dogging member mounted on said latch bolt for movements thereon between a dogging position locking said latch bolt against depression from said projected, latching position independently of said retracting mechanism and a non-dogging position releasing said latch bolt for depression; said biasing spring unit being connected with said dogging member and adapted

to act to continuously bias said dogging member from non-dogging position to dogging position; a constraining member positioned to be releasably engaged by said dogging member in projected position of said latch bolt to constrain said dogging member in non-dogging position; and said dogging member being adapted to be engaged with and moved by said latch bolt to position released from said constraining member for biasing by said spring unit to dogging position when said latch bolt is depressed from its said projected position independently of said retracting mechanism.

3. In a latch bolt mechanism, in combination; a case; a fixed abutment on said case; a latch bolt mounted in said case for movements to and from a latching position projected from the case; spring means connected with and adapted to continuously bias said latch bolt to said projected position; mechanism for retracting said latch bolt from its said projected position; said latch bolt being depressible from projected position against the action of said spring means independently of said retracting mechanism; a dogging member mounted on said latch bolt for movements thereon between a dogging position engaged with said abutment to lock said latch bolt against depression from its said projected position and a non-dogging position disengaged from said abutment to release said latch bolt for retraction; said latch bolt biasing spring means being also connected with said dogging member and being adapted to act to continuously bias said dogging member from non-dogging to dogging position on said latch bolt; said retracting mechanism including a constraining member mounted in position thereon adapted to be releasably engaged by and to constrain said dogging member in its non-dogging position in projected position of said latch bolt by said spring means and in all retracted positions of said latch bolt by said retracting mechanism; and said dogging member being adapted to be engaged by and moved to position disengaged from said constraining member for biasing by said spring means to dogging position by movement of said latch bolt from its said projected, latching position independently of said retracting mechanism.

4. In a latch bolt mechanism, in combination; a case; a latch bolt mounted in said case for reciprocation to and from a door latching position projected from the case; spring means adapted to continuously bias said latch bolt to said projected position; retracting mechanism engageable with said latch bolt for retracting the latch bolt from projected position; said latch bolt being depressible from projected position independently of said retracting mechanism; an abutment on said case; a dogging member mounted on said latch bolt for movements thereon between a dogging position engaged with said abutment to lock said latch bolt against depression from its said projected position independently of said retracting mechanism and a non-dogging position disengaged from said abutment to release said latch bolt for retraction; a blocking member mounted in said case for movements between a position blocking said abutment from engagement by said dogging member and position unblocking said abutment; an auxiliary bolt reciprocally mounted in said case for movements to and from position projected from the case, said auxiliary bolt being adapted to be depressed from projected position by engagement with a strike plate; said blocking member being

connected with and actuated by said auxiliary bolt to block said abutment with the auxiliary bolt in projected position and to unlock the abutment with the auxiliary bolt depressed; a constraining member on said retracting mechanism adapted to be releasably engaged by said dogging member to constrain the dogging member to non-dogging position with said latch bolt in projected and retracted positions; and said dogging member being mounted on said latch bolt for movement bodily therewith to position released from said constraining member when said latch bolt is depressed from its said projected, latching position independently of said retracting mechanism.

5. In a latch bolt mechanism, in combination, a case; a latch bolt mounted in said case for reciprocation to and from a latching position projected from the case; spring means adapted to continuously bias said latch bolt to said projected position; retracting mechanism engageable with said latch bolt for retracting said bolt from said projected position to retracted positions; said latch bolt being depressible from said projected position independently of said retracting mechanism; an abutment on said case; a dogging member mounted on said latch bolt for movements thereon between a dogging position engaged with said abutment to lock said latch bolt against independent depression from its said projected position to retracted position and a non-dogging position disengaged from said abutment to release said latch bolt for retraction by said retracting mechanism; means adapted to be engaged by and to constrain said dogging member to non-dogging position with said latch bolt in its said projected position; and said dogging member being mounted on said latch bolt for movement thereby from position engaged with to position disengaged from said constraining means for movement thereof to dogging position solely by initial movement of said latch upon depression thereof from its said projected position independently of said retracting mechanism.

6. In latch bolt mechanism, in combination, a case; a latch bolt mounted in said case for reciprocation to and from a latching position projected from the case; means for retracting said latch bolt from said projected position; said latch bolt being depressible from said projected position independently of said retracting means; an abutment on said case; a dogging member mounted on said latch bolt for movements between a dogging position engaged with said abutment when said latch bolt is in said projected position to lock said bolt against depression and a non-dogging position disengaged from said abutment; biasing means being connected with said dogging member adapted to bias said dogging member from non-dogging to dogging position; an auxiliary bolt reciprocally mounted in said case for movements to and from a position projected from and a position depressed into said case; said auxiliary bolt being provided with a blocking member movable therewith and positioned thereon to be interposed between said abutment and said dogging member with said auxiliary bolt in projected positions; and said blocking member being adapted to be moved by said auxiliary bolt to position removed from between said dogging member and said abutment with said auxiliary bolt in depressed position.

7. In a latch bolt mechanism, in combination, a case; a latch bolt mounted in said case

for movements between a latching position projected from the case and a retracted, unlatching position; said case providing an abutment surface; a dogging member mounted in said case for movements between a dogging position engaged with said abutment surface to lock said latch bolt against depression from projected to retracted, unlatched position and a non-dogging position disengaged from said abutment surface for retraction of said latch bolt; an auxiliary bolt mounted in said case for movements between a position projected therefrom and a position depressed thereto; and said auxiliary bolt being formed to provide a blocking portion adapted to be positioned by said auxiliary bolt when in projected position to block off said abutment surface from engagement by said dogging member and when said auxiliary bolt is in depressed position to be positioned thereby to clear and unblock said abutment surface for engagement by said dogging member.

8. In a latch bolt mechanism, in combination; a case; a latch bolt mounted in said case for reciprocation between projected position and retracted position; an auxiliary bolt mounted in said case for reciprocation between projected position and retracted position, said auxiliary bolt being mounted for depression from projected to retracted position independently of said latch bolt; means for retracting said latch bolt from projected position; means adapted to continuously bias said auxiliary bolt to projected position; said latch bolt being depressible from projected position independently of said retracting means; a fixed abutment on said case; a dogging member mounted on said latch bolt for movements thereby between a dogging position engaged with said fixed abutment and a non-dogging position disengaged from said abutment; means connected with said dogging member adapted to continuously bias said member from non-dogging position to dogging position; a constraining member mounted on said retracting means adapted to be located thereby in position to constrain said dogging member to non-dogging position with said latch bolt in projected position; said dogging member being adapted to be moved by said latch bolt to position released from said constraining member by depression of said latch bolt; and a blocking member on said auxiliary bolt adapted to be positioned by the latter to block said dogging member from engagement with said fixed abutment when said auxiliary bolt is in projected position and to clear said dogging member for engagement with said fixed abutment when said auxiliary bolt is depressed from its projected position.

9. In combination, a case; a latch bolt mounted in said case for reciprocation between projected position and retracted position; means including a yoke member reciprocally mounted in said case for retracting said latch bolt from its projected position; spring means interposed between said latch bolt and said yoke member adapted to continuously bias said latch bolt to projected position, said latch bolt being depressible from projected position independently of said yoke member; a fixed abutment on said case; a dogging member mounted on said latch bolt within said case and being movable bodily with and rockable independently on said latch bolt between a dogging position engaged with said fixed abutment and non-dogging position disengaged therefrom; said spring means being engaged with said dogging member and adapted to con-

tinuously bias said member from non-dogging to dogging position; constraining means on said yoke member adapted to be positioned thereby to engage said dogging member when said latch bolt is in its projected position to constrain said dogging member to non-dogging position; and said dogging member being adapted to be moved by said latch bolt to position released from said constraining means by depression of said latch bolt from its said projected position.

10. In a latch bolt mechanism, in combination; a case; a latch bolt including a tailpiece mounted in said case for reciprocation between a projected position and a retracted position; means for retracting said latch bolt including, a yoke member reciprocally mounted in said case and being engageable with said latch bolt tailpiece to retract said latch bolt from projected position; said latch bolt and tail piece being depressible from projected position to retracted position independently of said yoke member; a spring member mounted on said tailpiece between said latch bolt and the adjacent end of said yoke member adapted to continuously bias said latch bolt to its projected position; a fixed abutment in said case; a dogging member including, a leg rockably mounted on said tailpiece between said latch bolt and said spring member, and a dogging arm extended from said leg member and being rockable therewith between a dogging position engaged against said fixed abutment and a non-dogging position disengaged therefrom; and said spring member adapted to continuously bias said dogging member leg in a direction to move said dogging arm from non-dogging position to dogging position engaged with said fixed abutment.

11. In a latch bolt mechanism, in combination; a case; a latch bolt including a tailpiece mounted in said case for reciprocation between a projected position and a retracted position; means for retracting said latch bolt including, a yoke member reciprocally mounted in said case adapted to engage said latch bolt to retract the latter from projected to retracted position; said latch bolt and tailpiece being depressible from projected position independently of said yoke member; a spring member mounted on said tailpiece between said latch bolt and the adjacent end of said yoke member adapted to continuously bias

50

said latch bolt to projected position; said case being formed with an opening therein providing an abutment surface at one side thereof; and a dogging member including a leg rockably mounted on said tailpiece between said latch bolt and said spring member, and a dogging arm extended from said leg member and being rockable therewith between a dogging position with said arm projected into said case opening in engagement with said abutment surface and a non-dogging position with said arm disengaged from the abutment surface.

12. In a latch bolt mechanism, in combination; a case; a latch bolt mounted in said case for reciprocation between latching position projected from the case and retracted position; spring means adapted to continuously bias said latch bolt to said projected position; mechanism for engaging and retracting said latch bolt from said projected position; said latch bolt being depressible from projected position independently of said retracting mechanism; a fixed abutment in said case; a dogging member mounted in said case for movements between a dogging position engaged with said abutment to lock said latch bolt in projected position against depression and non-dogging position disengaged from said abutment to release said latch bolt for movement to dogging position; a constraining member mounted in position to be releasably engaged by said dogging member to constrain the latter member in non-dogging position when said latch bolt is in its projected position; and said dogging member adapted to be engaged by said latch bolt when depressed for displacement to a position released from said constraining member for movement of said dogging member to dogging position engaged with said fixed abutment.

GOTTHARD HAGSTROM.
